(57) **CLAIM**

The ornamental design for a two-speaker remote acoustic
hailing device, as shown and described.

DESCRIPTION

FIG. 1 is a perspective view of a two-speaker remote acoustic
hailing device, showing my new design.

FIG. 2 is a front elevational view thereof.

FIG. 3 is a rear elevational view thereof.

FIG. 4 is a left side elevational view .

FIG. 5 is a right side elevational view thereof.

FIG. 6 is a top plan view thereof; and,

FIG. 7 is a bottom plan view thereof.
